UNITED STATES PATENT OFFICE.

MINNIE M. HARMONY, OF CANTON, OHIO.

MAIL-BOX STATION.

Application filed April 28, 1926. Serial No. 105,117.

The invention relates to mail boxes, and more particularly to mail boxes for use along rural free delivery routes wherein it is desired to provide a station for a plurality of boxes each belonging to an individual who may live away from the main route; and the objects of the improvement are to provide stations including new and improved case sections providing compartments for a plurality of mail boxes, arranged so that the mail-carrier may fill all the boxes and take mail from one side of the case, and may leave packages in a top compartment provided with an inwardly swinging spring hinged door; and further objects of the invention are to provide individual boxes interchangeably fitting in any of the compartments, for use either as mail delivery boxes to be filled by the mail-carrier through a slot at one end and to be emptied by the box owner by means of a key locked hinged door at the other end, or for reverse mounting in a compartment for receiving out-going mail from the box owners through a slot at one end located on the same side as the locked doors of the in-coming mail receiving boxes, and provided with a locked door on its other end located on the same side of the case as the slots for the in-coming mail receiving boxes, the aforesaid boxes being interchangeable for use either as in-coming or out-going mail boxes, and there being in general one out-going mail box associated with a plurality of in-coming mail boxes in the case compartments.

A further object of the invention is to provide improved latch means for retaining the separate boxes in the compartments at the will of the box owner, such means being easily operable by the box owner upon opening the locked hinged door by the use of the owner's key, but being inoperable from an adjacent compartment, thereby preventing theft of the individual boxes or their contents except by the malicious use of a key to fit the individual box lock, or by malicious destruction of the box.

A preferred embodiment of the invention is illustrated in the accompanying drawing, forming part hereof, in which—

Figure 1 is a fragmentary perspective view of a station provided with a plurality of case sections having a plurality of box compartments with boxes therein for in-coming and out-going mail, and with a roof

section provided with a hinged end door for receiving packages;

Fig. 2, a sectional perspective view of one of the individual mail boxes; and

Fig. 3, a fragmentary longitudinal section 60 of the station, as on plane 3—3, Fig. 1.

Similar numerals refer to similar parts throughout the drawing.

The improved mail box station indicated generally at 10, may include corner legs 11 65 secured as by bolts 12 to the corners of a single tier mail box compartment sections 13, provided with upper end flanges 14 which may be secured as by bolts 15 with the lower end flanges 16 of another, and preferably identical, superposed mail box compartment section 13'.

The upper end flanges 14 of the upper section may be secured as by bolts 15 to the lower end flanges 20 of a roof section 21. 75 The roof section 21 is preferably provided with an in-swinging spring hinged end door 22 which may be pushed in by the mail-carrier for inserting parcels in the compartment 23 of the roof section 21. 80

The sections 13 are divided as by partitions 24 into a plurality of equal compartments 25 interchangeably receiving the improved mail boxes 26.

Each mail box 26 includes a bottom wall 85 27, upwardly extending side walls 28 and 28', one end wall 29 provided with a mail slot 30 and having an in-swinging slotted flap 31 for protecting the interior of the boxes from the elements, and another end 90 wall door 32 hinged as at 33 with a side wall 28 of the box and provided preferably at a central location along its side edge opposite the hinge with a key actuated lock 34.

Each box is moreover provided with a spring latch 35 having a downwardly extending latch tongue 36 projecting through a centrally located slot 27 in the bottom wall 27 of the box.

Each section of the mail station is provided with a double bottom wall including a lower imperforate wall 38 and an upper perforate wall 39 provided with a plurality of apertures 40 centrally located in each compartment 25 for receiving the tongue 36 100 of the spring latch 35.

By the above construction the mail box 26 may be inserted in any of the compartments 25 with either its mail slot end or locked door end appearing at a given side as 41 110

of the station, which may be here designated for convenience the carrier's side of the station.

The spring latch 35 of each box, having its downwardly extending latched tongue 36 projecting through the aperture 40 in the upper bottom wall 39 of a station section secures the box against lateral movement in the compartment, and the lower imperforate bottom wall 38 of the section prevents operation of the spring latch except from the interior of the box.

The bolt of the lock 34 of each box operates with a suitable flange 28^a on the wall 28' for locking the door 32 by means of a box owner's key.

Consequently each individual box may not be moved in or removed from its compartment without first opening the lock provided 20 end door 32 by the use of the owner's key or a duplicate thereof.

As illustrated in Fig. 1, the carrier's side 41 of the station discloses a plurality of compartments filled with boxes having their slot ends 20 at the carrier's side of the station, so that the postman may fill the separate boxes with mail through the several slots 30, and a single box for out-going mail having its lock door end 32 at the carrier's side for 25 opening by the use of a key kept by the postman, the slot end of this box being located opposite thereto at the box owner's side of the station, and the lock end of all 30 the other boxes being located at the box owner's side of the station.

When the station is thus arranged, the carrier may go to the carrier's side of the station as in a vehicle, fill each box with its mail through the slots 30, and remove out-going mail from the out-going mail box 40 having its locked door end at the carrier's side of the station, all without moving from his vehicle.

It is contemplated that a plurality of stations will be set up throughout a given country, and since each of the compartments is interchangeable, a box owner may purchase a box and take the same with him for use at whichever station is nearest his home, irrespective of how many times he may move.

I claim:

1. A mail box station having a mail-carrier's side and a box owner's side, and including a section having a plurality of box compartments, each compartment having a pair of opposite open ends, one end being at the carrier's side of the station and the other end being at the owner's side of the station,

a plurality of mail boxes, each box having a slotted end and a lockable door end opposite each other, each box interchangeably fitting in any of the compartments, and each box end interchangeably fitting either of the compartment open ends, some of the boxes 65 having their slotted ends at the carrier's side of the station and one of the boxes having its door end at the carrier's side of the station.

2. A mail box station including a section 70 having a lower imperforate bottom wall, and an upper bottom wall having apertures therein and spaced from the lower imperforate bottom wall, a plurality of box compartments in the section, each compartment 75 having a pair of opposite open ends, a mail box having a slotted end and a lockable door end opposite each other, the box interchangeably fitting in any of the compartments, and a catch operable from the interior of the box for cooperation with one 80 of the apertures in the upper bottom wall for retaining the box in any compartment.

3. A mail box station including a section having a lower imperforate bottom wall, 85 and an upper bottom wall having apertures therein and spaced from the lower imperforate bottom wall, a plurality of box compartments in the section, each compartment having a pair of opposite open ends, a mail 90 box having a slotted end and a lockable door end opposite each other, the box interchangeably fitting in any of the compartments, and either end of the box interchangeably fitting either of the compartment open ends, 95 and a catch operable from the interior of the box for cooperation with one of the apertures in the upper bottom wall for retaining the box in any compartment.

4. A mail box station including a section 100 having a closure panel including plural walls, one of the walls having apertures therein and being spaced from the other wall, and the other wall being imperforate opposite the apertures, a plurality of box 105 compartments in the section, each compartment having a pair of opposite open ends, a mail box having a slotted end and a lockable door end opposite each other, the box interchangeably fitting in any of the compartments, and a catch operable from the interior of the box for cooperation with one 110 of the apertures in one of the walls for retaining the box in any compartment.

In testimony that I claim the above, I 115 have hereunto subscribed my name.

MINNIE M. HARMONY.
